UNITED STATES PATENT OFFICE.

DARIUS T. PHILLIPS, OF CHICAGO, ILLINOIS.

WHEEL.

Application filed January 26, 1925. Serial No. 4,688.

The wheel of the present invention is of that type which employs individually mounted tread sections each adapted to be compressed when brought into contact with the ground; and the object of the invention is to provide mountings for the tread sections of such character as to prevent slipping, and to permit the sections to conform to the ground in such a way as to secure the greatest amount of efficiency.

The invention consists in the details of construction of the individual tread sections and to the manner in which the said sections are individually mounted upon the wheel, and also to the manner in which the individual sections are correlated to one another, and to the features of construction and combinations of parts hereinafter described and claimed.

20 In the drawings:

Figure 1 is a side elevation partly in section of a portion of a wheel embodying the features of my present invention;

25 Fig. 2 is a diagrammatic view showing a face view of the treads;

Fig. 3 is a diagrammatic view showing the edge of the wheel rim with the treads and spring connections removed;

30 Fig. 4 is a view, partly in section, of the edge of the wheel rim, with one of the treads secured thereto, the spring being shown in section;

35 Fig. 5 is a side elevation of one of the treads, showing the various positions assumed by the tread during its period of contact with the ground; and

Fig. 6 is a plan view of one of the tread sections, looking toward the inside surface thereof.

40 The wheel as a whole comprises a hub 10, from which extends a web 11 having on opposite sides thereof a plurality of radiating bracket flanges 12, the alternate flanges being on opposite sides of the web, as indicated in full and dotted lines in Fig. 1.

45 Each bracket flange 12 terminates at its outer end in an outwardly extended arm 13 which furnishes a mounting for a circular disk shaped supporting head 14, the heads being arranged alternately on opposite sides of the web.

50 Each of the disk shaped heads has formed on its outer face a boss 15 provided with a spiral groove 16 adapted to have the inner convolutions of a heavy coil spring 17 threaded thereon in such a way as to afford

a firm securement of the spring against the face of a disk head.

Each boss 15 is provided in its center with an outwardly tapering tongue 18 having flat sides 19 and provided in its center with a triangular orifice 20 so cut as to present its middle angle at a point coincident with the radial axis of the mounting as a whole.

55 The tongue 18 is embraced by a pair of spaced ears 21 which extend inwardly from the opposite sides of a slotted boss 22 and divided in the center by a cross cut 23 in width equal to the thickness of the tongue 18. The boss sections 22 are formed upon the surface of a circular spring base 24 which receives the outer turns of the spring 17, the boss sections 22 being provided with a spiral groove 25 to receive the convolutions of the spring. The ears 21 carry a cross pin 26 which normally bears against the outer rounded angle of the aperture in the tongue 18. As shown at the left of Fig. 1, the arrangement is such that when the 60 tread is in action on the ground the pin 26 will travel around the triangular aperture in a manner presently to be described.

65 The spring base 24 has formed on its under side a transversely extending sleeve 27 which terminates at its ends in a pair of recessed drum shaped heads 28, the outer open faces of which bear against a pair of ears 29 formed on the inner face of a tread plate 30 which, as shown, is in the form of a 70 parallelogram, with its major axis extending obliquely transversely with respect to the plane of the wheel as a whole. The tread 30 is recessed on its outer face to receive a block 31 of rubber or other material adapted to grip the ground and furnish 75 the tread surface.

80 The tread plate 30 is mounted to rock upon a transversely extending shaft 32 which passes through the ears 29 and 85 through the sleeve 27, and the tread plate and tread block are normally held in the tilted or forwardly canted position indicated in Fig. 5, by the action of a pair of oppositely acting coil springs 33 and 34 housed 90 within the recessed heads 28. Each spring has its innermost coil secured to the wall of the head 28 and its outermost coil in contact with the inner surface of the tread plate 30. The spring 33, however, is coiled 95 to expand, while the spring 34 is coiled to contract, and the latter spring has its free 100 105 110

end entered through an eye 36, so that the conjoint action of the two springs tends to lift one side of the tread plate and to depress the other into the position indicated in Fig.

5, which represents the tread turning down to meet the ground, with its forward corner A presented in position for the initial ground engagement. The tilting or canting movements of the tread sections are limited 10 by the provision of stop lugs 37 formed on the wall of the head 28, as indicated in Fig. 5.

Fig. 1 shows the treads of the wheel in normal or unpressed condition, but when the 15 wheel rests upon the ground and is subjected to the weight of the vehicle, truck, automobile, ordnance or the like, the lower center tread will be forced upwardly, with the cross pin 26 occupying a position at the inner widened end of the triangular orifice 20 in the coacting tongue 18. A certain amount of displacement from normal will also be imparted to the two immediately adjoining tread sections, which by reason of the overlapping oblique relation of the sections to one another will likewise be in parallel contact with the ground. This displacing action will tend not only to force the mountings upwardly against the tension of the 25 connecting springs, but will also tend to overcome the tilting action of the springs 33 and 34 and cause the treads to occupy a flat position upon the ground.

In these circumstances, if rotative power 30 is imparted to the shaft upon which the wheel is mounted, the inner or web portion of the wheel carrying the supporting head 14 and apertured tongue 18 will be permitted a limited free movement of rotation or 35 rolling upon the tread sections which are in ground contact, during which the connecting spring or springs will be flexed as well as compressed. This rolling movement will be limited by the circumferential width of the inner or base ends of the apertures 20, and will be exhausted as soon as the contact 40 is established between the cross pin 26 and the forward end of the corresponding aperture. This limited movement, however, 45 serves to greatly reduce any tendency to slip and lengthens the period of time during which each tread section will maintain ground contact, and thereby overcomes the slippage which would otherwise be inevitable in the use of a rigidly secured flat tread section, which, of course, does not maintain the rolling ground contact characteristic of the unbroken tread of an ordinary wheel. The present wheel, therefore, not only avoids 50 this slipping tendency, but by reason of the yielding character of the connections described is enabled to prolong the period of ground contact for each tread until the next succeeding tread has come into action, which 55 overlapping of the ground service of each

section is due both to the positioning of the sections in the manner shown and to the functioning of the resilient connections in the manner stated.

As indicated in Fig. 5, each section approaches the ground in such a way as to present an apex or corner for initial ground contact which insures a firm initial engagement with the ground, after which, as the wheel continues to rotate, each section will 75 be successively thrown into the middle position, and finally into the ultimate position, as indicated in dotted lines.

Not only do the sections overlap one another by reason of their obliquity, but also by reason of their staggered relation on opposite sides of the plane of the wheel, as shown in Fig. 2. This alternates the preponderance of ground contact, first on one side of the wheel center and then on the other, so that when working in soft ground each tread will come into position to at least partially engage a section of fresh ground measurably removed from the sphere of disturbance caused by the contact of the preceding tread sections. This is important, since it tends to prevent the acting tread section from crushing back the soil into the groove or rut previously formed by the passage of the wheel, and thereby insures a firm area of 95 ground engagement to each transaction.

The invention is one which is not only useful for service on tractors, trucks, or other heavy vehicles or appliances intended to operate in soft ground, but is also serviceable 100 for use on automobiles and other road vehicles as a substitute for pneumatic tires, since the arrangement is such that each section will progressively come into contact with the ground and will afford an ample degree of 105 resiliency to prevent excessive shocks or jars from being transmitted to the wheel axle, so that a safe, easy and smooth running ground contact is maintained at all times.

I claim:

1. In a wheel, the combination of a center portion, a plurality of independent tread sections, an intermediate connecting member for each tread section, to which the tread section is pivotally mounted, a pin and slot 115 rocking connection between each intermediate member and the center portion of the wheel, and a spring for each tread section interposed between the center portion of the wheel and the intermediate connecting 120 member.

2. In a wheel, the combination of a center portion provided around its periphery with a plurality of enlarged spring heads, each spring head being provided with a tongue 125 having an aperture enlarged in a circumferential direction towards its inner portion, a connecting member provided with an inwardly protruding portion carrying a pin adapted to move within said aperture, a 130

spring for each intermediate connecting section surrounding the tongue and the coacting protruding portion, and bearing at its inner end against the spring head and at 5 its outer end against the intermediate connecting portion, and a tread section for each connecting portion pivotally mounted thereon.

3. In a wheel, the combination of a center portion provided around its periphery with a plurality of enlarged spring heads alternately protruding on opposite sides of the plane of the wheel, each spring head being provided with a tongue having an aperture 10 enlarged in a circumferential direction towards its inner portion, a connecting member provided with an inwardly protruding portion carrying a pin adapted to move within said aperture, a spring for each intermediate connecting section surrounding the tongue and the coacting protruding portion, and bearing at its inner end against the spring head and at its outer end against the intermediate connecting portion, and a tread section for each connecting portion pivotally mounted thereon.

4. In a wheel, the combination of a center portion provided around its periphery with a plurality of enlarged spring heads, each 15 spring head being provided with a tongue having an aperture enlarged in a circum-

ferential direction towards its inner portion, a connecting member provided with an inwardly protruding portion carrying a pin adapted to move within said aperture, a 20 spring for each intermediate connecting section surrounding the tongue and the coacting protruding portion, and bearing at its inner end against the spring head and at its outer end against the intermediate connecting portion, and a tread section for each connecting portion pivotally mounted thereon.

5. In a wheel, the combination of a center portion provided around its periphery with portions having circumferentially elongated slots, a connecting member co-acting with each of the slotted members, and carrying a pin adapted to move freely in a circumferential direction from end to end of such slot, and a tread member carried by each of 45 50 said connecting members.

6. In a wheel, the combination of a center portion, a plurality of circumferentially arranged connecting portions, each carrying a tread member, and a pin and slot connection between each of the connecting members and the center portion for permitting 55 free circumferential movement of the center portion and connecting members with respect to one another.

DARIUS T. PHILLIPS.
